COMBINED FAN AND LIGHTING UNIT

Donald Angus McDonald, Sandringham House,
Shirley St., Nassau, Bahamas

Filed Mar. 27, 1967, Ser. No. 6,384

Claims priority, application Great Britain Jan. 11, 1967

Term of patent 14 years

(Cl. D23—140)

Fig. 1.

Fig. 2.

Fig. 3.

FIG. 1 is a front perspective view of a combined fan and lighting unit showing my new design;

FIG. 2 is an end elevational view thereof;

FIG. 3 is a rear perspective view from above and other end, and

FIG. 4 is an elevation in the direction of the arrow IV in FIGURE 2.

I claim:

The ornamental design for a combined fan and lighting unit, substantially as shown.
